MINNOW BUCKET

Andrew Keiding and Edgar L. Buerger,
Milwaukee, Wis.

Application January 28, 1950, Serial No. 7,546

Term of patent 14 years

(Cl. D58—17)

To all whom it may concern:

Be it known that we, Andrew Keiding and Edgar L. Buerger, citizens of the United States, residing at Milwaukee, in the county of Milwaukee and State of Wisconsin, have invented a new, original, and ornamental Design for a Minnow Bucket, of which the following is a specification, reference being had to the accompanying drawing, forming part thereof.

Fig. 1 is a view in perspective showing a minnow bucket, embodying our new design.

Fig. 2 is a view in side elevation showing the minnow bucket illustrated in Fig. 1.

Fig. 3 is a view in end elevation showing our new design.

Fig. 4 is a bottom plan view.

Fig. 5 is a fragmentary detail view in section on line 5—5 of Fig. 3.

We claim:

The ornamental design for a minnow bucket, as shown.

ANDREW KEIDING.
EDGAR L. BUERGER.
